UNITED STATES PATENT OFFICE.

GUST A. MAGNUSON, OF ROCK FALLS, ILLINOIS.

ANGLE-CUTTING GUIDE FOR LATHES.

Application filed October 16, 1920. Serial No. 417,288.

To all whom it may concern:

Be it known that I, GUST A. MAGNUSON, a citizen of the United States, and a resident of Rock Falls, in the county of Whiteside 5 and State of Illinois, have invented a new and useful Improvement in Angle-Cutting Guides for Lathes, of which the following is a full, clear, and exact description.

My invention relates to improvements in 10 angle-cutting guides for lathes, and it consists in the combinations, constructions and arrangements herein described and claimed.

An object of my invention is to provide 15 a simple device which may be attached to a lathe, and by means of which devices, such as bevel gears, bevel rolls, etc., may be readily and accurately cut.

A further object of my invention is to 20 provide a device of the type described for cutting bevels by means of an ordinary round nosed tool.

A further object of my invention is to 25 provide a device which may be readily attached to lathes of the existing types, or removed therefrom at will.

A further object is to provide an angle-cutting guide in which the angle may be adjusted to various degrees.

Other objects and advantages will appear 30 in the following specification, and the novel features of the invention will be particularly pointed out in the appended claims.

My invention is illustrated in the accompanying drawings, forming part of this application, in which

Figure 1 is a plan view of a portion of a lathe with my improved angle cutting guide in position,

Figure 2 is an enlarged sectional view of 40 a guide, and

Figure 3 is an enlarged sectional view through a swivel.

In the drawing, the head stock of the lathe is shown at 1. At 2 I have shown 45 a hinge block which is secured to the head stock by means of screws 3. The hinge block has pivotally secured thereto, at 4, a guide bar 5, this guide bar being preferably made or two separate pieces bolted together by 50 bolts, such as those shown at 6 and 7. The outer end of the guide block is recessed at 8 to receive a swivel block 9, having pivot lugs 10 which extend through openings in the guide bar. One of these pivot lugs is 55 threaded to receive a lock nut 11 (see Figure 3).

A rod 12 is threaded at 13 and passes through a threaded opening in the swivel block 9. The rod has a nut 14 disposed therein, against which the block bears. Each 60 end of the rod is provided with a slot 15, by means of which the rod may be turned to move it with respect to the swivel head.

Arranged to cooperate with the guide bar 5 is a roller 16 carried by an arm 17, 65 which has a reduced threaded portion 18 arranged to enter the boss 19, of the carriage 20, which ordinarily carries the stock gauge. This gauge may be removed and the arm 17 secured to the carriage in place thereof. 70

From the foregoing description of the various parts of the device, the operation thereof may be readily understood. In Figure 1, I have shown the work at 21. After determining the angle which it is 75 desired to cut on the work, the guide bar 5 is set at this angle by first unloosening the nut 11 and swinging the guide bar on the hinge pivot 4 to the proper angle, and then screwing the rod 12 until it rests 80 against the cross bar 22 on the head stock of the machine. The nut 14 then is tightened and also the nut 10, so as to lock the guide bar in its operative position. The carriage may now be moved to bring the tool 85 23 into engagement with the work. The roller 16 will be guided along the outer edge of the guide bar, so that the tool will follow the angle which the guide bar makes, from the outer edge of the work to the inner 90 portion thereof, thus accurately cutting the desired angle.

When it is desired to cut another angle, the rod 12 and the swivel head 9 are adjusted as heretofore described for the angle 95 desired.

The device consists of few parts, which are not liable to easily get out of order. The use of the device insures accuracy in cutting bevels, and at the same time, does 100 not require close application on the part of the operator, since the roller, in following the guide bar, insures accurate work.

I claim:

1. The combination with a lathe having 105 a carriage and a head stock, of a plate secured to said head stock, a guide bar having a hinged connection to said plate, said guide bar consisting of separate plates clamped together, a swivel block mounted 110 between the outer ends of said plates, said swivel block having a threaded opening, a

thrust rod having threads arranged to enter said opening, means for clamping said swivel block in any position with respect to the guide bar, a post rigidly secured to 5 said carriage, and a guide roller carried by said post and arranged to travel along one edge of said guide bar.

2. The combination with a lathe having a carriage and a head stock, of a guide bar 10 adapted to be hingedly mounted on said

head stock, said guide bar having a swivel block mounted on its outer end, said swivel block having a threaded bore therethrough, a threaded thrust rod arranged to engage the threaded bore of and to be supported 15 by said swivel bar, and means for clamping said swivel bar in any position with respect to said guide bar.

GUST A. MAGNUSON.
